(57) **CLAIM**

The ornamental design for a light emitting diode module, as
shown and described.

DESCRIPTION

FIG. 1 is a front, top, right perspective view of a light emitting diode module showing a first embodiment of our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a partial enlarged view thereof, as labeled with
symbol 8 in FIG. 1;

FIG. 9 is a partial enlarged view thereof, as labeled with
symbol 9 in FIG. 2;

FIG. 10 is a front, top, right perspective view of a light emitting diode module showing a second embodiment of our new design;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a partial enlarged view thereof, as labeled with
symbol 17 in FIG. 10;

FIG. 18 is a partial enlarged view thereof, as labeled with
symbol 18 in FIG. 11;

FIG. 19 is a front, top, right perspective view of a light emitting diode module showing a third embodiment of our new design;

FIG. 20 is a front elevational view thereof;

FIG. 21 is a rear elevational view thereof;

FIG. 22 is a left side elevational view thereof;

FIG. 23 is a right side elevational view thereof;

FIG. 24 is a top plan view thereof;

FIG. 25 is a bottom plan view thereof;

FIG. 26 is a partial enlarged view thereof, as labeled with
symbol 26 in FIG. 19; and,

FIG. 27 is a partial enlarged view thereof, as labeled with
symbol 27 in FIG. 20.
